L. G. KNAPP

Des. 96,482

COMBINED LAMP BASE AND FONT

Filed Sept. 19, 1934

Inventor:
Leland G. Knapp,
By Brummell, Green & Walder Atty.

UNITED STATES PATENT OFFICE

96,482

DESIGN FOR A COMBINED LAMP BASE AND FONT

Leland G. Knapp, Chicago, Ill., assignor to Montgomery Ward & Co., Incorporated, Chicago, Ill., a corporation of Illinois

Application September 19, 1934, Serial No. 53,326

Term of patent 14 years

To all whom it may concern:

Be it known that I, Leland G. Knapp, a citizen of the United States, residing at Chicago, in the county of Cook and State of Illinois, have invented a new, original, and ornamental Design for a Combined Lamp Base and Font, of which the following is a specification, reference being had to the accompanying drawing, forming a part hereof.

In the drawing the figure is a side view of a combined lamp base and font showing my new design.

I claim:

The ornamental design for a combined lamp base and font, as shown.

LELAND G. KNAPP.
